ERWIN D. LOWELL, OF CLEVELAND HEIGHTS VILLAGE, OHIO, ASSIGNOR TO THE AMERICAN FORK AND HOE COMPANY, OF CLEVELAND, OHIO, A CORPORATION OF OHIO.

PAPER CASING FOR AGRICULTURAL FORKS.

1,161,707.

Specification of Letters Patent. Patented Nov. 23, 1915.

Application filed September 4, 1915. Serial No. 48,966.

To all whom it may concern:

Be it known that I, ERWIN D. LOWELL, a citizen of the United States, residing at Cleveland Heights Village, in the county of 5 Cuyahoga and State of Ohio, have invented a certain new and useful Improvement in Paper Casings for Agricultural Forks, of which the following is a full, clear, and exact description, reference being had to the 10 accompanying drawings.

The object of this invention is to provide a simple, cheap and effective paper casing for the heads of agricultural forks, preventing their soiling, rusting or marring between the time of manufacture and delivery to the user. Heretofore it has been customary for the manufacturer or wholesaler to deliver such forks in a package containing a number of articles, so that, in selling a 15 single fork, it was necessary for the retailer to break the original package, and thus the unsold portions thereof became soiled, rusted or otherwise damaged, interfering with their ready sale. Moreover, in the handling of 20 bundles of forks by the freight men and ware-house men, the points of the tines frequently projected through the wrapping, and were thus injured. The idea of my invention is to make an effective individual 25 package of each fork so that it will remain protected during shipping and handling until finally sold.

I have discovered a very simple form of paper casing which may be made from a rectangular sheet of paper and by which the head, including tines and socket, are effectively protected. Furthermore, my casing is secured to the fork in such a manner that there is no tendency of the fork to slip within 30 the casing and poke holes through it. This is important, as these articles are not only frequently handled roughly in transit, but are usually stood on their points in the store, and the points, being quite sharp, 35 would ordinarily puncture a paper wrapping.

In the drawings, Figure 1 is a perspective view of my casing in place on a fork head. The remaining views respectively indicate, 40 on a smaller scale, the casing in various successive stages toward completion. Thus,

Fig. 2 shows a fork head with the casing given its first fold; Fig. 3 shows a fork head with the casing having a second fold; Fig. 4 shows the head with the casing having 55 its third and fourth folds; Fig. 5 is an edge view of the upper portion of Fig. 4; Fig. 6 shows the casing having a fifth fold; Fig. 7 is an edge view of a portion thereof; Fig. 8 is an edge view and Fig. 9 an end view 60 showing the casing having its final folds and ready for the stapling.

In the drawing, A indicates the three tines of a fork which are joined together and provided with a socket A¹ in any usual manner. B indicates the handle for such fork.

One of the advantages of my casing is that it requires no special cutting of the blank, a simple rectangular sheet of paper being used for this purpose. This sheet is materially longer than the fork head and something over twice as wide. The sheet is first placed with its intermediate portion 10 (Fig. 2) behind the tines, with the portion 11 substantially as wide as the fork head extending at one side, and the smaller portion 12 of the sheet lying at the other side. This portion 12 is then bent over onto the face of the fork head approximately along the line of the outermost tine A, thus producing 70 a flaring or trapezoidal fold or panel of paper, as shown in Fig. 2. The projecting portion 11 is then folded over, making another trapezoidal panel which lies against the panel 12. Fig. 3 shows the casing at 75 this stage, which, it will be seen, is a substantially flaring envelop inclosing the fork head.

The next operation is to so bend the paper of the casing as to make a reinforced protection for the points of the tines. This is 80 accomplished by bending on itself a portion of the envelop which projects beyond the tines. The projecting portion of the three panels 10, 11 and 12 is first bent rearward over these points to produce a short transverse panel 13 and then bent upwardly at 85 14. This is shown in Figs. 4 and 5. Now, the extreme end portion 14 is folded on itself to produce the flap 15 (Figs. 6 and 7), and then this flap 15 and the upper half of the 90 panel 14 is bent over onto the front of the fork so that two panels 16 and 17 are made

out of the panel 14. This brings the casing into the form shown in Figs. 8 and 9, from which it will be seen that, extending across the extreme end of the package is a reinforce composed on the front side of the double thicknesses 15 and 16 and on the rear side of the double thicknesses 13 and 17, this reinforce being in addition to the thicknesses 10, 11 and 12.

10 The inner portions of the panels 10, 11 and 12 which lie on opposite sides of the shank of the handle are bent over onto the panel 11, as shown at 18 and 19 in Fig. 9. This makes a complete reinforced envelop for the fork head.

15 In order to secure the parts of the envelop described to each other and prevent them shifting on the fork head I employ suitable wire fastenings or staples. Thus, 20 four staples 20 are shown passing through the various thicknesses of the transverse reinforce and located adjacent to the respective tines. Two staples 21 pass through the two bent over folds 18 and 19, and one staple 22 is employed in the middle portion of the casing adjacent to the edge of the panel 11 and extending through the three thicknesses 11, 12 and 10.

25 It will be seen that this casing is simply constructed, is cheap and at the same time effectively protects the fork head. It should be noted particularly that the extending of the casing over the shoulders of the fork and securing it at this point and also securing it at the end of the fork anchors the casing to the head, so that there is no tendency for it to shift thereon. While the sheet of paper need not be particularly heavy, bending it into the form shown gives it a tubular effect, so that it has considerable power to resist strains tending to double or buckle it. Therefore, when the fork is stood on a floor on its points, even if it be dropped with considerable force, the 30 points will not puncture the paper, as the whole tubular casing will move downwardly with the fork and there will be no relative movement between the fork and paper. This avoidance of relative movement is important in enabling such a paper casing to be effective.

35 It may be stated as an additional advantage of my invention that it provides a convenient surface for the printing of any suitable description or advertisement, as indicated by the lettering 30 in Fig. 1.

Having thus described my invention, what I claim is:

1. A paper casing for agricultural forks 40 consisting of a sheet doubled to make a substantial tube embracing the fork, the projecting portion of the sheet beyond the ends of the tines being doubled transversely on itself first in one direction and then in the other to make a reinforce across the points

of the fork and extending onto opposite sides thereof.

2. A paper casing for agricultural forks 45 consisting of a sheet doubled to make a substantial tube embracing the fork, the projecting portions of the tube beyond the shoulders of the fork head being doubled inwardly, a transverse doubled reinforce 50 consisting of a plurality of thicknesses of paper extending across the points of the fork and onto opposite sides thereof, and fastening devices for securing the transverse reinforce and the inward bends beyond the shoulders.

3. A paper casing for agricultural forks 55 consisting of a sheet doubled to substantially embrace the fork, the projecting portions of the sheet beyond the points of the tines being doubled in one direction and then the other to provide a trough-shaped reinforce of double thickness extending onto both sides of the package, and fastening devices extending through such reinforce and through the casing proper within the reinforce.

4. In a paper casing for agricultural forks, the combination of a sheet having an intermediate panel standing on one side of the fork and two edge panels overlapping each other on the other side of the fork, the end portions of such three panels being doubled as a unit in one direction and then the other to provide a transverse reinforce extending over the points of the tines onto both the front and rear side of the casing, and staples passing through the reinforce and the intermediate portion of the casing.

5. In a paper casing for agricultural forks, the combination of a sheet having an intermediate panel standing on one side of the fork and two edge panels overlapping each other on the other side of the fork, the end portions of such three panels being doubled as a unit in one direction and then the other to provide a transverse reinforce extending over the points of the tines onto both the front and rear side of the casing, the portion of the casing extending beyond the shoulders of the fork being doubled inwardly, and staples passing through the last mentioned inwardly doubled portions and through the transverse reinforce, thereby anchoring the casing to the fork head beyond the shoulder and beyond the points.

6. A paper casing for a single agricultural fork consisting of a sheet doubled to make a substantially flat tube inclosing the fork head, means for anchoring such tube effectively to the head to prevent relative movement between them, and a transverse doubled reinforce consisting of a plurality of thicknesses of paper extending across the points of the fork and onto opposite sides thereof.

7. A paper casing for agricultural forks consisting of a sheet doubled on itself to make a substantial tube embracing the fork, a reinforce across the ends of the tines composed of a plurality of thicknesses of paper doubled on itself back and forth to extend onto both sides and across the ends of the

tines, and staples passing through both portions of such doubled reinforce and through the intermediate tubular portion of the cas- 10 ing.

In testimony whereof, I hereunto affix my signature.

ERWIN D. LOWELL.
